UNITED STATES PATENT OFFICE.

GEORGE ALBERT CHADDOCK, OF LIVERPOOL, ENGLAND.

WEIGHT-CONTROLLED AIRSHIP.

1,401,461.

Specification of Letters Patent. Patented Dec. 27, 1921.

Application filed July 31, 1920. Serial No. 397,912.

To all whom it may concern:

Be it known that I, GEORGE ALBERT CHADDOCK, a subject of the King of Great Britain, and a resident of Liverpool, England, 5 have invented certain new and useful Improvements in a Weight-Controlled Airship, of which the following is a specification.

This invention has for its object the production of a weight controlled air ship preferably controlled by a novel method of propulsion in combination with the utilization of waste heat gases and alternate provision for insuring a supply of cool air through 10 protected inlet ports, under suitable control, so as to provide for the admission of cool air in a form to insure the displacement of inner warm air through exhaust ports also under suitable control and by such means 15 to bring about expansion of gas by heat or moderate compression by cooling as and when required. Outrigger planes and other auxiliary aids are also preferably provided to take up any loss of lift that may arise 20 when moving the propellers gradually from the position of vertical lift to that of combined lift and drive, or that of direct drive where ordinary screw propulsion methods 25 are adopted either wholly or partially. 30 These provisions will meet the various conditions that governments of different States will certainly impose in future in vessels carrying a large number of people on a long ocean voyage. The auxiliary aids to 35 propulsion are provided to insure a better screw thrust action than now obtains when in horizontal flight more particularly as the weight control of this form of ship is mainly based upon the great difference of density as be- 40 tween air and water and of air itself at varying altitudes as affecting screw propulsion. The screw principle, from the me- 45 chanical standpoint, being founded primarily on an unyielding base or pressure fulcrum, its efficiency in a yielding fluid like water is materially fortified by skin fric- 50 tion and closing in of the water behind the vessel or wake counter pressure on the propeller which materially helps to fortify the 55 yielding base. Air being 832 times less dense than water affords at once the best medium as a highway for rapid communica- 60 tion but the screw principle is very severely handicapped in such a light fluid 65 prone to move, according to its own laws, on lines of least resistance. It follows when

an aerial propeller is first started a partial void is created in the disk area into which the air flows from all directions. Immediately axial advance commences or when the 60 air is driven rearward there is a constant induction of air toward the propeller disk by reason of the air flowing toward the area of depression of an advancing or stationary propeller thus materially undermining the 65 thrust value. A primary object of this invention is therefore to so control the inflow of air into the propeller disk area as to overcome the disability attendant upon air moving of its own accord on lines of least 70 resistance and to utilize that principle as far as possible as an aid to propulsion instead of detracting therefrom as now obtains. With this object the ship is constructed to admit of its propellers operating in a 75 shielding space in which they are protected from the effects of outer passing air at the sides. For this purpose a shielding plane or lower bow extension is fitted on each side at the bow, carried out far enough and high 80 enough to shield the propellers behind it, the rear part of this plane being sloped to an angle of approximately 45 degrees to admit or air being drawn down behind it. The effect of this procedure in practice will 85 be that as the vessel moves horizontally through the atmosphere the propellers operate in a shielded area and are thus freed from air that has been given propulsion momentum in the direction of the shaft line. 90 Moreover the passing air ceases its shaft line motion over the well instantly the attraction ceases and before it comes under the suction control of the propeller next behind it has to pass the intermediate plane set at 95 an angle to induce a following wake as a further corrective against momentum on the shaft line. In this connection there is a further corrective agency operating against such air momentum arising by reason of the 100 friction and elastic properties of the air tending to create the equivalent extraction experienced in buildings when a volume of air passing a door inlet sucks out such a volume of air from inside as to cause vio- 105 lent closure of the door. Something of the equivalent of this suction effect will be induced by air passing over the upper part of the well and thus act as a pull against propellers thereby enhancing their thrust 110 effect, this tendency to create an upcast from the well will also be aided by the upper

planes the drag action of which should cause the air underneath and close to the rear of the plane to flow into the partial void set up by the vessel and planes rapid 5 advance. The lower plane acts to cut off the side suction on under side of propeller blades. The general downcast will have the combined effect of drawing air away from the pressure area at bow and friction area 10 at sides of hull and tend to fill up the void or area of retarding suction at the stern or lower section thereof. As there are two stream lines in this ship one from passing air and one induced by propulsion action 15 the artificial air movement should have a material effect upon the ordinary stream line displacement. There being an outer screen fixed to prevent side inflow of air the full power of all the propellers can be concentrated on shaft line suction and rearward 20 drive free from the disabilities now ruling with propellers operating on lines of axial advance where the disk area becomes surcharged with air moving in freely and rapidly 25 on lines of least resistance. The auxiliary aids so fitted as an aid to propulsion will offer slightly more resistance than a vessel with a clean hull but the extra resistance will be out of all proportion to the 30 additional speed gained by the very great increase in thrust value added to which there will be a secondary stream line set up by the large volume of air drawn down through the protected well thus tending to 35 lessen resistance to progress in horizontal motion. These auxiliary aids while effective in horizontal motion have little or no effect on thrust value in a vertical lift as the downward momentum of air is not cut 40 off or retarded in a vertical lift which process of direct lift is however aided by the use of internal heat which can be brought into operation on starting engines prior to ascending. The total engine power being 45 applied to drive a number of propellers operated along each side of the ship the maximum volume of air is utilized for propulsion purposes which cannot be efficiently attained by any other procedure. It follows 50 the ship is borne through the air by power pressure evenly distributed in a form to avoid any undue strains being set up in any part of the hull and also to provide such a number of engine and propeller units as to 55 render compulsory descent for overhaul of engines unnecessary as there will be abundant reserve power to provide for sustentation while any deranged units may be under overhaul. Provision is made in the construction of this ship for the complete isolation of passengers and crew from the gas containing portion of the ship thereby leaving the main hull, excepting navigation 60 room and passage ways clear, for the use of 65 internal gas as an aid to weight control and thereby reducing the diameter and consequent area of wetted surface and weight of water therefrom when rising as well as checking rolling effect and added weight of water therefrom. These side carrying 70 stabilizing chambers are divided up to enable the engines to be carried at a height sufficient to insure a free flow of internal gas under such complete control as to avoid the dangers of any direct connection between 75 the engines and internal gas bags. For this purpose intermediate gas containers are fitted on engine decks with gas tight valves between these containers and inner gas bags also between the auxiliary containers and 80 engines. By these means enough internal gas may be consumed to balance the weight of petrol used or to make the ship heavy or light by varying the mixture which will add very materially to the efficiency of a 85 weight controlled ship driven on lift drive principles. This principle of free or pressure flow gives command of the flow when at less than the pressure height and guards against the dangers of back firing where the 90 vacuum in the induction pipe is relied upon to suck down the gas. These provisions for the use of a mixture as and when required will tend to keep the engine cleaner and provide for easier starting particularly under 95 extreme cold at high altitudes which is a material factor in aerial weight control. The vessel's bottom being of wood will act as a good heat retainer and thereby enable the air beneath the gas bags to be quickly 100 heated whereas with a fabric cover this heat would be dissipated but, by concentrating on the air in the heat containing space, expansion of internal gas is quickly facilitated. The provision of air ports and admission thereby of cool air not only facilitates weight control but will prove a necessary factor even when such a ship is not in flight to counteract the effect of exterior 105 heat and by the means described complete 110 temperature control is effected.

According to this invention, the hull of the weight controlled airship is so shaped as to afford the minimum suction resistance in rising from the water and a maximum resistance to air pressure when descending. The passenger and engine decks and side structures are so disposed as to concentrate the structural weight and the disposable load well below the center of gravity of the ship 115 insuring stability and also that the flat under surfaces shall be well above the deep load line so as to avoid suction thereunder when rising while offering a large resisting surface during descent. The invention further 120 relates to means whereby the waste heat gases from the engines are led to an inner receiver in the ship's hull whereby the explosive noises are silenced and the otherwise waste heat utilized to bring about internal 125 130

expansion of air or for warming the passengers' quarters. Further features of the invention relate to means for effecting and controlling a supply of cool air to the interior in order to expel the warmer air therefrom and so bring about a moderate compression of gas when carried inside the ship; to the arrangement and disposition of the propellers suitably spaced along the sides of the ship in such manner that the angle of the propeller shafts may be varied to permit of the propellers effecting a direct lift or a combined lift and drive; to means for inclosing the propellers by outer screens to form a well of sufficient depth to protect the propellers when working at any angle whereby the maximum thrust of the propellers may be obtained; to means for sheathing a portion of the hull of the ship so as to isolate the main hull from the passenger, crew, and engine accommodation, and to means for protecting the ship from external danger by providing a depending wire or cable acting as a lightning conductor.

25 The invention is illustrated in the accompanying drawings, in which Figure 1. is a side elevation of the airship broken away centrally. Fig. 2. is a sectional plan on line 2—2 of Fig. 1 showing the arrangement of the propellers and engines and end planes, Fig. 3. being a plan on line 3—3 of Fig. 1 showing the lower passenger decks, corridors, berthing and crew accommodation. Fig. 4. is a fragmentary cross-section of the lower part of the ship showing the disposition of the propellers, engines, crew and passenger accommodation. Fig. 5. is a fragmentary detail view showing the operating rods and gear for controlling the angular movement of the propellers. Fig. 6. is a detail showing the outer screen inclosing the propellers and Fig. 7. is a diagrammatic view showing the outrigger planes and side support fitted between the propellers. In Fig. 2 the propellers are shown at an angle of direct lift but the screen is removed on the port side to conform with Fig. 1 in which figure the screen in order that the propeller at angle of lift drive may be set out in contrast to position of propellers when operating at angle of direct lift set out in Fig. 2 on the starboard side on which the screen is shown also intermediate outrigger planes between each propeller.

55 In carrying out the invention, the hull 1 of the ship is preferably provided with a strong outer sheathing in the water borne section say of wood to insure temperature control of the inner gas also to reduce to a minimum water suction when rising and to provide the maximum air resistance when descending. For this purpose the large part of the bottom 3 extending outward, on each side, from the central portion of the hull is so shaped as to offer sufficient

resistance to prevent rapid descent also to prevent undue list, the gross internal weight carried being also so disposed as to preclude any dangerous angle being taken up. By means of the form of construction shown at 2 the ship is enabled to float on water with a minimum suction resistance to direct lift on rising, a strong watertight outer shell being provided, if desired, around the entire ship, in such manner as to insure as far as possible complete temperature control. For this purpose air ports, 4, 5, are fitted and controlled so that the temperature of the inner air may be regulated to help bring about gas expansion if installed or carried by closing the air ports and using the waste heat gases to heat the air beneath the gas bags and thereby facilitate gas expansion or the ports, 4, 5, may be opened to bring about moderate gas compression by permitting the circulating of cold air around exterior of gas bags as, and when desired. With such provision the exhaust heat from the engines can be used internally for heating the inner air to facilitate gas expansion or the heat shut off and cold air allowed to circulate around the outside of the gas bags inside the ship as required to counteract the effect of exterior or interior heat. In Fig. 4 the piping 30 is shown as led from engines on each side of the ship to receiver 31 for utilizing waste heat gases to heat air beneath the gas bags. The provision made for cool air supply should provide for moderate gas compression without the aid of fans, but such may be fitted if required, and warm air outlets closed to increase the gas compression, this temperature control thereby materially assisting in insuring weight control. Provision is made as an aid to gravity control for the consumption of such relative proportion of gas as may be considered advisable from time to time either as a means of counteracting expansion or to assist in preserving complete weight control by consuming any relative proportion of gas that may be considered requisite to neutralize the decrease in weight carried owing to consumption of fuel, oil or stores, during the voyage or for any requirement. For these purposes and in order that internal gas may be under complete control suitable auxiliary gas containers 6 are fitted preferably on the upper deck provided with connections forming gas leads one of which will be connected with the internal gas bag or bags and the other connecting the auxiliary gas bag or gas container to the engine or engines to control the supply, both of these leads being fitted with gas tight valves in a form to isolate the engine from the auxiliary gas bags or containers as and when required, also the latter from the internal gas bags when not requiring a supply therefrom.

Suitable provision is made for the economical consumption of hydrogen or coal gas, as well as petrol as and when required in all or any desired engine or engines. The provision thus made will insure weight control in a ship driven by existing system of propulsion in which propellers 7 may be mounted, at a suitable spacing, on the propeller supports 14, 15, shown along each side of the ship.

In the arrangement shown in the drawings the propellers 7 are driven by bevel gearing 8 through side shafts 9 from the engines 10 and means are provided for varying the angular direction of the axis of rotation of the propellers. A suitable arrangement is shown in Fig. 5, where the engines are mounted upon geared quadrants 11 engaging a rack 12 which runs fore and aft on the engine deck and is operated in any suitable manner by a gear wheel or wheels 13.

The arrangement of propeller supports, 14, 15, extends sufficiently far out from the side of the ship to enable the propellers to be rotated well clear of the vessel's side and are attached to the vertical sides 16 of hull in a manner to permit of being stayed against both lift and driving strains and by means of the angular adjustment admit of the propellers carried being oscillated to any desired angle of drive or to operate as a direct vertical lift, when desired, as an aid to weight control.

In order to increase the weight control the propellers 7 are shielded by a plane or planes or bow extension or extensions 17 Fig. 1, so constructed as to enable propulsion to be carried on with a propeller working at an angle of combined lift and drive in such manner as to enable a greater efficiency to be exercised and a larger load carried when the vessel is in motion through the atmosphere thereby materially increasing weight control and adding to the speed of the ship.

And as a further aid to weight control and speed with such form of propulsion side screens 18 and outrigger planes 19 are provided with suitable stern extensions 19^a, and ridge rods 19^b connect and tie together the fore and aft end planes 17, 19^a, and the outrigger planes 19 carry the ridge rods, which latter stay the outrigger planes and support the side screens 18. The horizontal strains on the outrigger planes are opposite in direction to those on the propeller supports, and by connecting the outer ends of these planes 19 and the extensions 19^c of the horizontal propeller supports, the strains on the propeller supports are partly neutralized.

These planes are designed as an aid to the system of propulsion to partially compensate for any loss in lift which may otherwise take place in moving a propeller from the position of direct lift to that of combined lift and drive or in the case of ordinary

screw propulsion to that of direct drive. The planes 19 generally will therefore be designed and set at an angle to take up the approximate equivalent amount of lift that may be sacrificed in the process of moving propellers from the position of direct lift to that of angle of drive, or lift drive for horizontal speed through the atmosphere. The planes thus also act as an aid to gravity control but a further material function is the general provision made for drawing air away from a pressure area particularly at the bow. One of the main objects of the screen 18 is to prevent the propellers being exposed to the effect of passing air, particularly in any turning movement, and to enable the suction effect of propellers to be regulated to advantage. A further action of the screens 18 is to enhance the thrusting action of the propellers 7 when acting as a direct lift from the water surface or otherwise.

The dotted lines 20 Fig. 1, indicate approximate spacing of main girders and inner spaces for gas bags. Rudders 21 are fitted at extreme ends on ship for vertical control. The lower passenger decks, corridors 22 and berthing communication shown in Fig. 3 is preferably divided at 23 into separate sections with communication doors controlled by attendants so as to localize the disposable weight of the passengers.

The propeller control system which enables the propeller or series of propellers to be turned while in motion or at rest from a drive to a lift action, under ordinary method of propulsion, will act as a weight correction agent, in any emergency particularly in event of leakage in any gas bag. These conditions also apply to the propulsion system, when working in a screened deep well of still air, more particularly as any side list or end tipping can be instantly compensated when in motion without loss of time in moving propellers to a lift position, this is a most essential feature in a passenger ship. A further important feature of this invention is that the engines are so inclosed as to render their action or working almost noiseless, for this purpose the pipe leads for escape gases, may be connected with a central receiver or receiver on each side, to so deaden the noise of explosion as to enable the vessel to proceed through the atmosphere at a reasonable height without disclosing her presence to those below, for this purpose the decks, sides, and bottom may be constructed to break up sound waves externally and internally as between the two or more decks. The decks, side and bottom may be of wood in the form of an outer and inner flooring with strengthening timbers between or metal may be used where desired and the deck or decks or some portion thereof take the form of tanks for fuel, oil and water. The en-

gines may be so mounted as to be secured in any position of lift or drive or combined lift and drive. The engine is shown in Fig. 5 at 11 as bound down by its operating rod 5 and thus secured when the propeller is in the position of direct lift as at 28° and likewise forced against a buttress or chock when the propeller 28 is in the position of drive lift. The third position where the propeller 10 28° is shown at an angle of direct drive is merely to indicate that it can, by the controlling apparatus, be given a wider range than that of direct lift and lift drive as shown at 28° as the engine can be so mounted 15 and controlled as to command sternway for docking or hovering if desired.

In order to support the bow end plane 17 a stay rope 24 may be carried around the bows to link up these planes on either sides 20 or linked up with outrigger planes in a manner to help neutralize the strains on propeller supports.

And the front end planes 17 may be modified as indicated by the dotted lines 17a to 25 limit any undue lifting tendency at the bow.

Horizontal steering rudders 25 are fitted to the bow.

As shown in Fig. 7, the outrigger planes are rigidly distanced by vertical struts 26 30 and braced to the sides 16 by ties 27.

I claim:

1. A weight controlled air ship comprising a main hull fitted with exterior protected air wells on each side open to the air 35 above and below between end planes and outrigger plane spaces in which propellers operate, said wells being formed by projecting planes fitted at the bow and stern on each side and extending outward from the 40 hull far enough to shield the propellers from passing air, outrigger planes being interposed between the propellers on each side, side screens attached to outer ends of bow and stern planes, a series of propellers operated one behind the other in the shielded 45 controlled air spaces provided to improve the lift drive thrust of propellers when in horizontal flight.

2. A weight controlled air ship comprising a main hull fitted with exterior protected air wells on each side open to the air above and below between end planes and outrigger plane spaces in which propellers operate, said wells being formed by projecting planes fitted at the bow and stern on each side and extending outward from the hull far enough to shield the propellers from passing air, outrigger planes being interposed between the propellers on each side, side screens attached to outer ends of bow and stern planes, a series of propellers operated one behind the other in the shielded 55 controlled air spaces provided to improve the lift drive thrust of propellers when in horizontal flight, side carrying chambers ex- 60 terior to and bulkheaded off from main hull for the accommodation and isolation from main hull of passengers, crew, engines, fuel, stores and all equipment, the carrying chambers being fitted above the water line also 70 act as stabilizers on the water or in the air.

3. A weight controlled air ship comprising a main hull fitted with exterior protected air wells on each side open to the air above and below between end planes and 75 outrigger plane spaces in which propellers operate, said wells being formed by projecting planes fitted at the bow and stern on each side and extending outward from the hull far enough to shield the propellers from 80 passing air, outrigger planes being interposed between the propellers on each side, side screens attached to outer ends of bow and stern planes, a series of propellers operated one behind the other in the shielded 85 controlled air spaces provided to improve the lift drive thrust of propellers when in horizontal flight, and shielding end planes on each side at the front and rear of the propellers and staying means for said side 90 screens.

4. A weight controlled air ship comprising a main hull fitted with exterior protected air wells on each side open to the air above and below between end planes and outrigger 95 plane spaces in which propellers operate, said wells being formed by projecting planes fitted at the bow and stern on each side and extending outward from the hull far enough to shield the propellers from passing air, outrigger planes being interposed between the propellers on each side, side screens attached to outer ends of bow and stern planes, a series of propellers operated one behind the other in the shielded controlled air 100 spaces provided to improve the lift drive thrust of propellers when in horizontal flight, and rods for utilizing the rearward strains on outrigger planes to assist in counteracting the horizontal drive portion of strain on 105 propeller supports.

5. A weight controlled air ship comprising a main hull fitted with exterior protected air wells on each side open to the air above and below between end planes and 110 outrigger plane spaces in which propellers operate, said wells being formed by projecting planes fitted at the bow and stern on each side and extending outward from the hull far enough to shield the propellers from 115 passing air, outrigger planes being interposed between the propellers on each side, side screens attached to outer ends of bow and stern planes, a series of propellers operated one behind the other in the shielded 120 controlled air spaces provided to improve the lift drive thrust of propellers when in horizontal flight, and means for oscillating the engines to vary the plane of rotation of the propellers as an aid to weight control 125 130

6. A weight controlled air ship comprising a main hull fitted with exterior protected air wells on each side open to the air above and below between end planes and 5 outrigger plane spaces in which propellers operate, said wells being formed by projecting planes fitted at the bow and stern on each side and extending outward from the hull far enough to shield the propellers from 10 passing air, outrigger planes being interposed between the propellers on each side, side screens attached to outer ends of bow and stern planes, a series of propellers operated one behind the other in the shielded 15 controlled air spaces provided to improve the lift drive thrust of propellers when in horizontal flight, and auxiliary gas containers adjacent to engines to receive gas from gas bags from main hull and to supply engines with fuel, said containers being placed 20 sufficiently high to insure a free flow of gas from the gas bags in main hull and then to engines for increased weight control, the connections between said auxiliary gas containers and main gas bags and between auxiliary containers and engines being fitted 25 with gas tight valves.

7. A weight controlled air ship comprising a main hull fitted with exterior protected air wells on each side open to the air above and below between end planes and 30 outrigger plane spaces in which propellers operate, said wells being formed by projecting planes fitted at the bow and stern on each side and extending outward from the hull far enough to shield the propellers from 35 passing air, outrigger planes being interposed between the propellers on each side, side screens attached to outer ends of bow

and stern planes, a series of propellers operated one behind the other in the shielded controlled air spaces provided to improve the lift drive thrust of propellers when in horizontal flight, and a receiver in the main hull of the ship and piping conveying the 40 waste heat gases to the receiver whereby such waste heat gases may be used for heating internal air under gas bags to facilitate internal gas expansion as an aid to weight control. 50

8. A weight controlled air ship comprising a main hull fitted with exterior protected air wells on each side open to the air above and below between end planes and outrigger plane spaces in which propellers 55 operate, said wells being formed by projecting planes fitted at the bow and stern on each side and extending outward from the hull far enough to shield the propellers from passing air, outrigger planes being interposed 60 between the propellers on each side, side screens attached to outer ends of bow and stern planes, a series of propellers operated one behind the other in the shielded controlled air spaces provided to improve 65 the lift drive thrust of propellers when in horizontal flight, air inlets below the side carrying chambers and air outlets controlling a supply of cool air to the interior of the hull for temperature and ballast weight 70 control.

In testimony whereof I affix my signature in presence of two witnesses.
